RAYMOND R. TAYLOR, OF ROCHESTER, NEW YORK.

DENTAL X-RAY-FILM PACKET.

1,394,503.

Specification of Letters Patent. Patented Oct. 18, 1921.

Application filed January 8, 1919. Serial No. 270,167.

To all whom it may concern:

Be it known that I, RAYMOND R. TAYLOR, a citizen of the United States, residing at Rochester, in the county of Monroe, State of New York, have invented a new and useful Improvement in Dental X-Ray-Film Packets, of which the following is a specification.

This invention relates to a dental X-ray film package of the kind in which the films are individually packed and marketed; and in which the films are exposed to the action of X-rays, the package not being opened until after exposure.

15 The objects of my invention are to provide a package of this kind which is easy and inexpensive to manufacture, which has no protruding points or corners, the surface being smooth and non-irritating and the corners rounded, so that it may be used in a patient's mouth with the minimum of inconvenience; which is so constructed that it may be readily opened in the dark or in a very dim light, and prepared for development with the greatest facility. The other 20 objects will appear in the description following.

Reference will now be made to the accompanying drawings, in which Figure 1 is a 25 perspective view of the packet assembled and ready for use; Fig. 2 is a perspective view of the packet, as torn open; and Fig. 3 is a section of the packet as assembled and used.

30 Like reference characters refer to the same parts throughout the drawings.

The packet comprises two sensitized films, 17^a and 17^b, in contact with each other, and lying between front and back protective 35 light seals 18 and 16, made of light proof paper slightly larger than the films. Around these elements is folded the cover comprising the inner and outer sheets 15 and 11. The inner cover sheet 15 is made 40 of light proof paper or cloth or a combination of both, and outer cover sheet 11 is made of a water and light proof paper or cloth or a combination of both. These two cover elements are larger than the films and 45 the protective sheets 16 and 18 and their edges are folded around these and partially over the rear surface of sheet 16.

A cloth or fiber strip 14 is provided to act as a means for opening the packet easily. 50 It passes through a slit in sheet 16 and one end lies between this sheet and film 17^a,

lengthwise of the packet. The other end extends from the slit out over the sheet 16 and the overturned edge of sheet 11, midway of one side of the packet. As indicated 55 clearly in Fig. 2, the strip is larger at the end within said packet so as to tear open a wider portion thereof when in use.

A sealing strip 12, made of the same material as sheet 11, is, when the packet is 60 otherwise completely assembled, laid upon the packet and securely pressed against the overlapping edges of 11 and the face of sheet 16, where it is held in place by suitable cement, glue or mucilage.

The sheet 11 forms the front face 10, and the emulsion sides of the film face toward it. The packet is intended for use, as is customary, in the patient's mouth, behind the teeth, and with the face 10 toward the 65 source of X-rays, where it is held in position during exposure by the fingers of the operator or patient or by any other available means. It will be obvious that, as the corners are rounded, and the packet smooth 70 except for the tab, that the patient will undergo only very slight inconvenience.

The purpose of the sheet 15 is to guard 75 against light entering through possible pin holes or incomplete opacity of the sheet 11, while 16 and 18 add a further assurance 80 against the same defect, sheet 16 additionally guarding against light leaks between sheet 12 and the overturned edges of 11.

After an exposure has been made, the 85 packet is taken to a dark room where it is opened for the removal of the film for development. The user need not fumble in the dim light of the dark room to open the 90 packet, but merely grasps the tab and pulls 95 it back across the rear surface of the packet. As the tab runs beneath sheets 16 and 12 across the central part of the film area, and as it is larger at its inner end, the back of the package is so disrupted that the remaining rims of the back can be easily 100 grasped and the enveloping sheets removed from the films with ease.

While this specific embodiment of my invention is described, it is understood that I 105 contemplate the substitution of such equivalent structures as are embraced within my invention as defined in the claims.

Having thus described my invention, what I claim as new and desire to secure by Letters Patent is:

1. A package of dental X-ray film com-

- prising a sheet of sensitized film, a sheet of protective material on each side thereof, the sheet on one side being impervious to light and pervious to X-rays, and the sheet on the other side being impervious to light, these two protective sheets being sealed at their edges to form a tight envelop, a strip of material extending across one surface of the film and beneath a portion of one protective sheet and extending through the joint between the protective sheets to form a tab, which may be manipulated to disrupt one of the protective sheets.
2. A package comprising a sheet of sensitive material, a protective sheet on each side thereof, a protective envelop containing said sensitized material and said first named sheets and a strip of material lying partially beneath one of said inner protective sheets and extending through said envelop to form a tab, by manipulation of which the protective sheet and envelop may be disrupted to furnish access to the sensitive material.
3. A dental X-ray film package comprising a sheet of sensitive material, a sheet of protective material on one side thereof, two sheets of protective material on the other side thereof, the edges of the first named sheet being bent around the edges of the film and lying between the edges of the two sheets on the other side, the outer sheet being adhesively joined to such turned over edge, and a strip extending through such adherent joint and through the inner protective sheet to furnish means for tearing open the package.
4. A dental X-ray film packet comprising a sheet of sensitized film, protective sheets on each side of said film, the edges of one being bent around the edges of the film and
- the second sheet, the second sheet having a slit therein, a rip strip, the greater portion of which lies between the film and the slotted sheet, and which passes through the slit and continues in the same direction across the package beyond the edge thereof, and a sealing strip secured to the turned over edges mentioned and to the second sheet and to the strip.
5. A dental X-ray film package comprising a sheet of sensitized film, a protective sheet of greater dimensions than said film upon one side thereof, the edge portions of the sheet being bent around the edge of the film, a protective sheet on the other side of the film having a slit therein, the edges of which lie under the bent over edges of the first named sheet, a sealing strip coated with an adhesive material and pressed into adhesive contact with the second sheet and the edges of the first sheet, and a strip extending across the package, the major portion thereof lying between the film and the second named protective sheet, and passing through the above mentioned slit, and a portion thereof lying between the slotted sheet and the sealing strip and a small tab portion extending out between the sealing strip and the turned over edge specified above, the tab serving as a handle whereby the strip may be manipulated to tear open the central part of the package.
- In witness that I claim the foregoing I have hereunto subscribed my name this sixth day of January, 1919.
